UNITED STATES PATENT OFFICE.

ROBERT WORLEY RHODES, OF GREENSBURG, PENNSYLVANIA.

SCRAPER.

Application filed February 24, 1922. Serial No. 538,843.

To all whom it may concern:

Be it known that I, ROBERT W. RHODES, a citizen of the United States, residing at Greensburg, in the county of Westmoreland, 5 State of Pennsylvania, have invented a new and useful Improvement in Scrapers, of which the following is a full, clear, and exact description, reference being had to the accompanying drawings, forming part of 10 this specification, in which—

Figure 1 is a side elevation of a scraper embodying the present invention;

Figure 2 is a front elevation of the construction illustrated in Figure 1;

15 Figure 3 is a detail view of the supporting member for the blade;

Figure 4 is a sectional view on the line IV—IV of Figure 3;

20 Figures 5 and 6 are detail views of the backing member;

Figure 7 is a perspective view of the clamping strip for the backing member;

Figure 8 is a sectional view, partly in elevation, illustrating the handle in reversed 25 position;

Figure 9 is a side elevation of a slightly modified form of scraper;

Figure 10 is a top plan view of the construction illustrated in Figure 9;

30 Figure 11 is a perspective view of the foot for the scraper illustrated in Figures 9 and 10;

Figure 12 is a detail view of the supporting member for the scraper illustrated in 35 Figures 9 and 10;

Figure 13 is a side elevation of a still further modified form of scraper;

40 Figures 14 and 15 are detail views illustrating parts of the construction shown in Figure 13;

Figure 16 is a sectional view illustrating a modified form of adjusting means for the scraper blade, and Figure 17 is a detail view of one form of blade which may be 45 used.

The present invention relates broadly to wood working tools and more particularly to a scraper for smoothing and finishing surfaces such as floors and the like.

50 At the present time it is quite customary to scrape floors for the purpose of finishing the same. Various forms of scrapers for this purpose have been designed, but practical objections to the use thereof have 55 presented themselves. With certain types

of scrapers it has been necessary to re-sharpen the same by curling or turning the operating edges of the blade. This has been a delicate operation requiring considerable skill. With still other types of scrapers, 60 the handles have been so mounted as to prevent the use of the scraper adjacent walls. Accordingly, it has been necessary to provide separate scraping tools for use there-with.

65 The present invention obviates the objections referred to, and provides a scraper having a blade which may be easily sharpened to provide an actual cutting edge as distinguished from a turned edge, and in 70 which the blade may be easily adjusted to vary the depth of cut. In accordance with one feature of my invention, there is also provided a scraper of the type in which the handle may be reversed relatively to the 75 scraping blade to permit the scraper to be either pulled or pushed as required by the conditions under which the scraper is being operated.

80 Referring more particularly to Figures 1 to 8 of the drawings, there is illustrated a scraper comprising a supporting member 2 which is preferably of curved or segmental shape, as shown. This member is provided with threaded pins 3 projecting 85 therefrom and adapted to pass through openings 3^a in a blade 4 whereby the blade may be maintained in definite position with respect to the supporting member. The blade is preferably of wafer-like thickness 90 to provide flexibility permitting it to be clamped firmly against the surface of the supporting member by means of a curved backing member 5. This backing member is provided with elongated openings 6 95 adapted to receive the pins 3 and permit relative adjustment between the supporting member and the backing member. When the desired adjustment is secured, the parts may be clamped in position by tightening 100 the nuts 7 against the flat surface of a clamping strip 8 having openings 9 to receive the pins 3 and a curved surface 10 conforming to the curvature of the backing member.

105 For adjusting the members 2 and 5, the supporting member is provided with racks 11 extending on opposite sides of the cut-away central portion 12. The backing member is provided with spaced projecting bear- 110

ings 13 adapted to extend partly through the cut-away portion 12 of the supporting member when the parts are in cooperative position, as clearly shown in Figure 1. Extending through the openings 14 in the bearings 13 is a hub 15 having formed on the outer ends thereof pinions 16, the teeth of which are adapted to mesh with the racks 11. Extending diametrically through the hub 15 is a threaded opening adapted to receive the threaded end 17 of the handle bar 18. Mounted on the handle bar adjacent the bearings 13 is a handle 19 having a sleeve-like collar 20 through which the handle bar 18 loosely passes. One end of the collar 20 is concaved as indicated at 21 to cooperate with the circular faces of the bearings 13. Secured to the outer end of the handle bar 18 is a second handle 22.

With the construction described, when it is desired to effect relative adjustment between the members 2 and 4 to retract or project the blade 4, the handle 22 is rotated to unscrew the end 17 from the hub 15. This releases the clamping action between the collar 21 and the bearings 13, and permits the pinions 16 to be rotated by relative movement between the handle bar 18 and the supporting member 2. Rotation of the pinions 16 in a clockwise direction as viewed in Figure 1, such as would be produced if the handle 22 is swung upwardly in the direction of the arrow A, is effective for retracting the blade 4, while rotation of the pinions 16 in a counterclockwise direction as viewed in Figure 1, by movement of the handle 22 in the opposite direction, projects the blade 4. When the desired positioning of the blade is secured the clamping nuts 7, which were loosened to permit this adjustment, will again be tightened, and the handle 22 will be rotated to screw the threaded end 17 into the hub 15 and thereby hold the parts against movement. It will also be apparent that any desired angular relationship between the blade 4 and the handle bar 18 may be effected by changing the relationship of the teeth of the pinions 16 with respect to the racks 11.

When it is desired to sharpen the blade 4, it is only necessary to loosen the nuts 7, loosen the handle bar 18 and move the handle bar in the direction of the arrow B to project the blade for its full distance. The blade may then be sharpened on a stone in the usual manner.

In Figure 8 of the drawings the handle bar 18 is illustrated as having been entirely released from the hub 15 and again screwed thereinto from the opposite side of the hub. This permits the scraper to be pushed if desired, while with the parts in the position illustrated more particularly in Figure 1, the scraper is adapted to be pulled.

The backing member 5 gives support to

the flexible blade 4 adjacent its cutting edge and also serves as a stop, cooperating with the amount of projection of the blade and the angular position of the handle bar 18 for controlling the depth of the cut.

In Figures 9 to 12 of the drawings there is illustrated a slightly different embodiment of the present invention, and for the sake of brevity, I have indicated the parts of these figures which correspond to parts already described by the same reference characters with a prime affixed thereto. With this construction the handle bar is omitted and the parts are clamped in position by a clamp screw 23 having a thumb nut 24. The clamping screw 23 has a clamping washer 25 of elongated shape similar in construction to the clamping strip 8 heretofore described, and adapted to bear against the periphery of the bearings 13'. 70

With this form of my invention the supporting member 2', in addition to the pins 3', has projecting rearwardly therefrom pins 26 adapted to pass through slots 27 in a curved member 28 having a foot 29 formed thereon. The member 28 may be clamped in the desired position by nuts 30. Secured to the member 28 is a cross bar 31 having its opposite ends angularly bent as illustrated in Figure 10 to receive handles 32 by which the scraper may be either pulled or pushed. I have found that with a construction of this character the foot 29 effectively cooperates with the blade to prevent chattering thereof. 85

In Figures 13 to 15, there is illustrated another modification having the parts thereof corresponding to the parts already described in detail in connection with Figures 1 to 8 indicated by the same reference characters with an *a* affixed thereto. In this form of 100 my invention the handle bar is adapted to pass through a tubular sleeve 33 having a tubular projection 34 threaded in its interior and adapted to receive the foot 35. It will be apparent that the foot 35 corresponds 105 generally in function to the foot 29 heretofore described.

In Figure 16 I have illustrated a slightly modified construction adapted particularly to the forms of the invention illustrated in 115 Figures 1 to 8 and Figures 13 to 15, for changing the position of the blade without changing the angular relationship of the blade with respect to the surface being scraped. In accordance with this feature of 120 my invention the hub 15 has projecting from one side thereof a hollow interiorly threaded boss 36 adapted to receive the threaded end 17 of the handle bar. The pinions 16 are adapted to be formed on the 125 opposite ends of a rod 37 rotatably mounted within the hub 15 which in this case is of sleeve-like formation. The rod 37 is tapped to receive an operating pin 38 and the hub 15 has a slot 39 to permit the rod 37 and 130

the pinions to be rotated relatively to the hub without changing the angular position of the handle.

The edges of the backing members 5, 5' 5 and 5^a are all preferably constructed with beveled edges 39 permitting the scraper to more closely scrape adjacent corners and the like.

The advantages of the present invention 10 arise from the provision of a scraper adapted to employ a flexible scraping blade which may be easily sharpened or adjusted as found necessary. Further advantages arise from the construction permitting the scraper 15 to be either pulled or pushed whereby an entire job may be finished by the use of a single implement.

I claim:

1. In a scraper, a supporting member, a 20 backing member, a flexible blade, adapted to be held in fixed position with respect to one of said members, means for clamping said blade in position between said members, said members being operative to curve the blade 25 by the clamping operation, means for adjusting one of said members relatively to the other to vary the amount of projection of said blade therebeyond, and a handle for operating said scraper, substantially as de- 30 scribed.

2. In a scraper, a supporting member, a backing member, a flexible blade, adapted to be held in fixed position with respect to one of said members, means for clamping said 35 blade in position between said members, said members being operative to curve the blade by the clamping operation, means for adjusting one of said members relatively to the other to vary the amount of projection 40 of said blade therebeyond, a handle for operating said scraper and a foot cooperating with said blade, substantially as described.

3. In a scraper, a supporting member, a 45 backing member, a scraping blade of wafer-like thickness adapted to be held in fixed position with respect to one of said members, means for clamping said blade in position between said members, said members being operative to curve the blade by the 50 clamping operation, means for adjusting one of said members relatively to the other to vary the amount of projection of said blade, and means for operating said scraper, substantially as described.

4. In a scraper, a supporting member 55 having a pin projecting therefrom, a backing member having an elongated opening to receive said pin, a blade adapted to be held by said pin in fixed relation to said sup- 60 porting member, means for clamping said blade in position between said members, and an operating handle for effecting relative adjustment between said members to vary the amount of projection of said blade, sub- 65 stantially as described.

5. In a scraper, a supporting member having a pin projecting therefrom, a backing member having an elongated opening to receive said pin, a blade adapted to be held by said pin in fixed relation to said sup- 70 porting member, means for clamping said blade in position between said members, an operating handle for effecting relative ad- 75 justment between said members to vary the amount of projection of said blade, and a 75 foot cooperating with said blade, substan- tially as described.

6. In a scraper, a supporting member hav- 80 ing a rack formed thereon, a backing mem- ber adapted to cooperate therewith and hav- 85 ing a bearing projecting therefrom, a pinion in said bearing adapted to mesh with said rack, a blade, means for clamping said blade in position between said members, and means for adjusting said pinion to vary the 85 amount of projection of said blade, substan- tially as described.

7. In a wood-working tool, a scraping 90 blade of wafer-like thickness, and means for curving the blade and for supporting the scraping edge of said blade, substantially as described.

8. In a wood-working tool, a flexible blade of wafer-like thickness, supporting members 95 for curving said blade, and means for pro- 95 ducing relative adjustment between said members to vary the amount of projection of said blade, substantially as described.

9. In a wood-working tool, a scraping 100 blade of wafer-like thickness, means for curving the blade and for supporting the cutting edge of said blade, and means co- 105 operating with said blade to maintain the same in definite angular relation to the surface being scraped, substantially as de- 105 scribed.

10. In a wood-working tool, a flexible 110 scraping blade, supporting members adapt- ed to receive and clamp said blade therebe- 110 tween under tension, means for varying the amount of projection of said blade, and means cooperating with said blade to main- 115 tain the same in definite angular relation with respect to the surface being scraped, substantially as described. 115

11. In a scraper, a supporting member, a 120 backing member, a flexible blade, adapted to be held in fixed position with respect to one of said members means for clamping said blade in position between said members, 120 and an operating handle effective for ad- justing one of said members relatively to the other to vary the amount of projection of said blade therebeyond, said backing member having beveled edges, substantially 125 as described.

12. In a scraper, a supporting member, a 130 backing member, a flexible scraping blade adapted to be held in fixed position with respect to one of said members, means for 13

4
clamping said blade in position between said members, said members being operative to curve the blade by the clamping operation, and an operating handle operatively connected with said members for varying the amount of projection of said blade by adjusting one of said members relatively to the other, substantially as described.

13. In a scraper, a supporting member having a rack formed thereon, a backing member adapted to cooperate therewith and having a bearing projecting therefrom, a pinion in said bearing adapted to mesh with said rack, a blade, means for clamping said blade in position between said members, and an operating handle for operating said scraper and adjusting said pinion to vary the amount of projection of said blade, substantially as described.

20 14. In a wood-working tool, a flexible scraping blade of wafer-like thickness, supporting members for curving said blade for projecting its cutting edge toward the work to be scraped, and an operating handle for 25 producing relative adjustment between said

members to vary the amount of projection of said blade, substantially as described.

15. In a wood-working tool, a supporting member, a backing member, a flexible blade adapted to be held in fixed position with respect to one of said members, and means for clamping said blade to hold the same under tension between said members to project the cutting edge in the direction in which the scraper is operative, substantially 30 as described.

16. In a wood-working tool, a supporting member, a backing member, a flexible blade adapted to be held in fixed position with respect to one of said members, means for 40 clamping said blade to hold the same under tension between said members to project the cutting edge in the direction in which the scraper is operative, and means for varying the amount of projection of said 45 blade beyond said members, substantially as described.

In testimony whereof I have hereunto set my hand.

ROBERT WORLEY RHODES.
